UNITED STATES PATENT OFFICE.

SAMUEL J. FISHER, OF ASHEVILLE, NORTH CAROLINA.

ATTACHMENT FOR BATH-TUBS.

1,054,834.

Specification of Letters Patent. Patented Mar. 4, 1913.

Application filed May 6, 1912. Serial No. 695,553.

To all whom it may concern:

Be it known that I, SAMUEL J. FISHER, a subject of the King of England, residing at Asheville, in the county of Buncombe and State of North Carolina, have invented certain new and useful Improvements in Attachments for Bath-Tubs; and I do hereby declare the following to be a full, clear, and exact description of the invention, such as will enable others skilled in the art to which it appertains to make and use the same.

My invention relates to attachments for bath-tubs, and it consists in the constructions, combinations and arrangements hereinafter described and claimed.

The object of my invention is to provide an improved attachment for bath-tubs comprising a portable shower bath, lavatory, and sitz bath in compact form for convenient use in transportation, and adapted to supply all the conveniences and luxuries of a complete modern bath room to tourists and to occupants of flats or other contracted quarters.

In the accompanying drawings forming a part of the application, and in which similar reference symbols indicate corresponding parts in the several views:—Figure 1 is a fragmentary longitudinal section through the spigot end of a bath-tub, illustrating one embodiment of my invention applied thereto and adjusted to constitute a shower bath; Fig. 2 is a transverse section of a bath-tub, showing my invention applied thereto for providing a lavatory at convenient height for use; Fig. 3 is an enlarged, detail view, illustrating a preferred hose connection to the annular spray device and the support for a soap dish thereon; Fig. 4 is an enlarged fragmentary view of the pivotal connection between two adjacent legs of the lazy tongs constituting my adjustable member; Fig. 5 is an end view of the construction shown in Fig. 4, with the pivotally connected legs folded in their closed position; and Fig. 6 is a fragmentary elevation of a modification.

Referring to the drawings, 1 indicates brackets slidably mounted on the rim of a bath-tub 2, and provided with set screws 3 for rigidly securing them in place if desired. The brackets 1 are provided with pins 4 for slidably engaging the slotted lower legs of lazy tongs 5, and with vertical slots 6 intermediate of said pins for slidably engaging the lowest pivot bolts 7 of said lazy

tongs; said bolts 7 being provided with heads 8 engaging the rear faces of the brackets 1 and with wing nuts 9 for securely clamping the lazy tongs in their several adjusted positions. A hollow annular seat 10 is provided with pins 11 slidably engaging slots in the upper legs of said lazy tongs for interchangeably supporting various bathing vessels, such as a lavatory or a sitz bath, at different desired heights for convenient use.

Fig. 2 shows a lavatory 12 extending through the annular seat 10 and supported in convenient position thereon at any desired height within a bath-tub by its curled rim 13; a sitz bath 14 similarly supported on the annular seat 10 being indicated by broken lines. The hollow annular seat 10 is provided with a series of perforations 16 to constitute a spray device, and is connected to the bath-tub spigot 15 by a flexible hose 17; said connection being conveniently made by a coupling member 18 swiveled on the end of the hose 17 for threadingly engaging a nipple 19 extending from the hollow annular spray device.

Figs. 4 and 5 illustrate a construction, in which the pivoted legs of the lazy tongs are provided with raised ends 20 formed with ribs 21 and recesses 22 for frictionally resisting shifting of the lazy tongs and yieldingly locking said pivoted legs together in the closed or contracted position of said tongs.

Fig. 6 illustrates a modified construction, in which a link 23 is pivoted on the bolt 24 of the lazy tongs and provided with slots 25 adapted to receive an upper bolt 26 of the lazy tongs, said slots being formed with recessed portions 27 for lockingly engaging said bolt 26. The lower legs of the lazy tongs are shown provided with projecting stops 28 for firmly supporting the lazy tongs in collapsed or closed position.

I have illustrated and described preferred and satisfactory constructions, but changes could be made within the spirit and scope of my invention.

I claim:—

1. An attachment for bath-tubs, comprising an adjustable member, means for detachably supporting said member on a bath-tub, a hollow annular seat carried by said member for interchangeably supporting a lavatory or sitz bath at different desired heights, said hollow seat being perforated

to constitute a spray device, means for connecting said spray device with the usual bath-tub nozzle, and means for locking said member in its several adjusted positions.

- 5 2. An attachment for bath-tubs, comprising lazy tongs, having their terminal legs provided with slots, brackets for detachably supporting said tongs on a bath-tub and provided with pins slidably engaging the lower slotted legs of said tongs, said brackets being provided with vertical slots medially of said pins, pivot bolts on said lazy tongs extending through such bracket slots for clampingly locking said lazy tongs in their

several adjusted positions, a hollow annular 15 seat provided with pins slidably engaging the upper slotted legs of said lazy tongs for interchangeably supporting a lavatory or sitz bath at different heights, said hollow seat being perforated to constitute a spray 20 device, and means for connecting said spray device with the usual bath-tub nozzle.

In testimony whereof, I affix my signature, in presence of two witnesses.

SAMUEL J. FISHER.
